UNITED STATES PATENT OFFICE.

ARTHUR J. COUGHTRY, OF BROOKLYN, NEW YORK.

COLLAPSIBLE LADDER.

1,217,279.

Specification of Letters Patent. Patented Feb. 27, 1917.

Application filed August 10, 1914. Serial No. 856,021.

to all whom it may concern:

Be it known that I, ARTHUR J. COUGHTRY, a citizen of the United States, and a resident of Brooklyn, in the county of Kings and State of New York, have invented a certain new and useful Collapsible Ladder, of which the following is a specification.

This invention has for its object the production of a collapsible ladder particularly applicable for use on board ships; and it consists in the combinations and constructions hereinafter set forth and claimed.

In describing this invention, reference is had to the accompanying drawings, in which like characters designate corresponding parts in all the views.

Figures 1 and 2 are elevations of a preferable embodiment of this ladder showing the same as fully extended and as partially extended.

Fig. 3 is an elevation showing the ladder collapsed.

Fig. 4 is a front elevation of the upper portion of the ladder when partially extended.

Fig. 5 is a fragmentary view of the ladder.

Fig. 6 is a plan view of one of the steps.

Fig. 7 is an elevation of two units of another form of this ladder.

Fig. 8 is a plan view of parts seen in Fig. 7.

This ladder comprises, generally, longitudinally telescoping units, and means for folding the units collapsed, and for holding some of the units but partly extended or partly collapsed when the next unit is collapsed therein so that the distance between all steps in effective position is uniform. More specifically, it includes side rails, each composed of telescoping sections paired with the sections of the other rail, and a step supported by each pair of sections except the top section. The top unit may or may not support a step, but is provided with means as hooks which engage a support for the ladder. Hence, the ladder is usually suspended from its top and rests on the deck at its base.

1 designates the sections which are inflexible and preferably tubular in form with the possible exception of the top section 2 which may be solid if desired, as there is no section to telescope within the same. The sections 1 of each rail are paired with those of the other rail and support at their upper ends the steps 3.

The steps are formed with hubs 4 which

receive the upper ends of the rail sections of the corresponding units, and the steps extend laterally beyond the rails and provide lugs 5* which are formed with open-ended slots 5 for a purpose to be presently described. Each section is also formed with a lengthwise slot 6 in which projects a shoulder 7 provided on the next higher section. The shoulders 7 prevent the sections from being pulled apart or separated, by engaging the upper ends of the slots 6.

The top sections 2 are, for obvious reasons, not provided with the slots 6, but are provided with the shoulders 7, and the base unit 70 is not provided with the shoulders. The top unit is provided with suitable hooks 8 for engaging any suitable part for supporting the ladder, as the coaming around the hatches, and the base sections are provided 75 with feet 9 including rubber rings which engage the deck and prevent the base of the ladder from slipping, the rubber rings being held in collars 10 on the lower or base sections of the ladder rails. In the use of the 80 ladder, the feet prevent the ladder from swinging into a vertical line when the hooks 8 are engaged with the coaming, and hold the ladder always at the same inclination whether it is fully extended or partly collapsed so that the tread surfaces of the steps 85 are always horizontal.

The means for holding the units in collapsed position and for spacing the effective steps equidistant apart when one or more 90 sections are collapsed, comprises members, as latches 11 common to all the units and pivoted at 12 to collars 13 which are preferably provided on the upper ends of the sections of the unit next below the unit formed with 95 the hooks 8, said members 11 being usually bars movable laterally on their pivots 12 into and out of the slots 5 on the steps and having a series of shoulders 14 for hooking under the lugs 5* when said members are in the 100 slots 5, as seen in Fig. 3, the members 11 also having additional shoulders 15 at their ends for hooking under the first step below the unit to which the latches are secured when the ladder is extended to its full extent, Fig. 105 1, or into the step of the second unit from that to which the latches are pivoted when the intermediate unit is collapsed into the unit supporting the third step from the top, as shown in Fig. 2.

By reason of the members 11, the steps in effective position are spaced uniformly

apart, as for instance, when the section carrying the topmost step is collapsed into the section carrying the second step from the top, the latter section is partly collapsed 5 and the shoulder 15 engaged with the third step from the top while the uppermost shoulder of the series 14 is engaged with the second step from the top, as clearly seen in Fig. 2. Hence, the topmost step and the 10 third step from the top are spaced the same distance apart as the underlying steps. The shoulder 7 on the top section 2 prevents the top section and next lower from separating, and the uppermost shoulder 14 locks the 15 second section to the first from the top so that they act as a unit. Hence, when the parts are in their position shown in Fig. 2, one section is practically eliminated.

Instead of being formed tubular, the telescoping sections, as seen in Figs. 7 and 8, may be otherwise formed to collapse or overlap each other, and they may be formed of channel irons 17 which are formed with lengthwise slots 18 and shoulders 19 corresponding to the slots 6 and shoulders 7 of the tubular construction. The steps in the construction shown in Figs. 7 and 8 are formed from strips of flat metal bent inverted U shape in general form, the legs 25 of the U formation engaging the backs of the channel irons, which face outwardly and the intermediate portions thereof forming the steps proper.

This ladder is particularly advantageous 35 in that it can be collapsed into a small space for stowing and when extended to different heights the treads of the steps thereof will be a uniform distance apart, and always in a horizontal plane as the ladder 40 will always have the same incline to whatever height it is extended.

What I claim is:—

1. A collapsible ladder comprising longitudinally telescoping units, and means for 45 supporting an intermediate unit from collapsing when occupying a position between its fully collapsed and extreme extended positions whereby the distance between the ladder steps in effective position is uniform, 50 substantially as and for the purpose described.

2. A collapsible ladder comprising longitudinally telescoping units, and means for supporting an intermediate unit from collapsing 55 when occupying a position between its fully collapsed and extreme extended positions whereby the distance between the ladder steps in effective position is uniform, said means being secured to one unit of the 60 ladder, and movable into interlocking engagement with the partly collapsed lower unit, substantially as and for the purpose specified.

3. A collapsible ladder comprising side 65 rails each composed of telescoping sections

paired with the sections of the other rail, steps supported by the rails, spacing means secured to one pair of sections and movable into interlocking engagement with another pair spaced apart from the former pair when 70 the ladder is extended, substantially as and for the purpose described.

4. A collapsible ladder comprising longitudinal telescoping units, and a member common to all the units secured to one unit 75 and having means for interlocking with other units when the ladder is collapsed and holding the ladder in collapsed position, substantially as and for the purpose specified.

5. A collapsible ladder comprising longitudinal telescoping units, and a spacing member secured to one unit and having means for interlocking with the second lower unit when the unit to which said member is 85 secured is collapsed, and the first lower unit is partly collapsed into said second lower unit, substantially as and for the purpose set forth.

6. A collapsible ladder comprising longitudinal telescoping units, and a spacing member secured to one unit and having means for interlocking with the second lower unit and the first lower unit when the unit to which said member is secured is collapsed, 95 and the first lower unit is partly collapsed into said second lower unit, substantially as and for the purpose described.

7. A collapsible ladder comprising longitudinally telescoping units, and a latch pivoted to one unit and having a series of shoulders arranged to interlock with the other units when the ladder is collapsed, substantially as and for the purpose specified.

8. A collapsible ladder comprising side rails, each composed of telescoping sections paired with the sections of the other rail, and members pivoted to opposite sides of one section and movable on their pivots into interlocking engagement with a plurality of the other sections, substantially as and for the purpose set forth.

9. A collapsible ladder comprising side rails each composed of telescoping sections paired with the sections of the other rail, each section having a lengthwise slot and a shoulder for entering the slot of the next lower section, substantially as and for the purpose described.

10. A collapsible ladder comprising side rails each composed of telescoping sections paired with the sections of the other rail, and having lugs projecting laterally beyond the rails and formed with open-ended slots, and a latch pivoted to one section and movable on its pivot into the slots of the lugs and having shoulders for engaging undersides of the lugs when said member is in the slots, substantially as and for the purpose specified.

11. A collapsible ladder comprising longitudinally telescoping units having means for preventing the same from pulling apart or separating entirely or beyond a distance for correct spacing of steps when extended, and spacing member secured to one unit and having means for interlocking with the second lower unit and the first lower unit when the unit to which said member is secured is collapsed into the first lower unit below the same, and said first lower unit is partly collapsed into the second lower unit, substantially as and for the purpose set forth.

12. A collapsible ladder comprising side rails, each composed of telescoping sections paired with the sections of the other rail, each section having a lengthwise slot and the shoulder for entering the slot of the next lower section and engaging the upper end wall thereof to prevent separating of the sections, and a spacing member secured to the unit and having means for interlocking with the second lower unit and also with the first lower unit when the unit to which said member is secured is collapsed into the last lower unit and said first lower unit is

partly collapsed into the second lower unit, substantially as and for the purpose described.

13. A collapsible ladder comprising side rails each composed of telescoping sections paired with the sections of the other rail, each section having a lengthwise slot and a shoulder for entering the slot of the next lower section and engaging the upper end wall thereof to prevent separating of the sections, the sections having laterally extending lugs provided with open-ended slots and a latch pivoted to one section and movable on its pivot into the slots and having shoulders for engaging the undersides of said lugs when said latch is in the slots, substantially as and for the purpose specified.

In testimony whereof, I have hereunto signed my name in the presence of two attesting witnesses, at Brooklyn, in the county of Kings, in the State of New York, this 24th day of July, 1914.

ARTHUR J. COUGHLTRY.
